UNITED STATES PATENT OFFICE.

JOHN J. MANN, OF SEATTLE, WASHINGTON.

OIL-BURNER.

1,069,091.

Specification of Letters Patent. Patented July 29, 1913.

Application filed February 4, 1913. Serial No. 746,154.

To all whom it may concern:

Be it known that I, JOHN J. MANN, citizen of the United States, residing at Seattle, in the county of King and State of Washington, have invented a certain new and useful Improvement in Oil-Burners, of which the following is a specification.

My invention relates to improvements in burners adapted to burn fluid fuel such as crude oil, kerosene, gasolene, and the like, but more particularly my invention relates to such burners that may be employed in connection with stoves adapted for heating or cooking, and the object of my invention is to provide a burner that shall be simple in its construction, easily cleaned, comparatively inexpensive to manufacture, reliable and efficient in its operation, and that shall be adapted to utilize for its fuel different mineral oil products, and a further object of my invention is to provide a burner that may be readily attached to various forms of common stoves that are now in general use. I attain these objects by the devices illustrated in the accompanying drawings where-

Figure 1 is a view in front elevation of a burner embodying my invention associated with portions of a stove which are shown in vertical section; Fig. 2 is a view in vertical section of the same on the line α , α , of Fig. 1, Fig. 3 is a plan view of a burner embodying my invention showing a portion of an asbestos mat on which it rests, and Fig. 4 is a view in front elevation of a burner embodying my invention wherein some of its parts are of a modified form.

Like reference numerals indicate like parts throughout the drawings.

Referring to the drawings, 5 is the circular base portion of a burner, preferably of cast iron, having its bottom end convex and its top surface slightly concave. Extending upwardly from opposite points on the top of and out of the base 5 are the two end portions 6, 6, of a pipe which is curved helically to form a cylindrical coil 7 disposed concentrically with the circle of the base 5 and above the cylindrical coil 7 the said pipe is formed to make a loop 8 which extends across from one side of the cylindrical coil 7 to its opposite side, and centrally disposed in the under side of said loop 8 is a small

hole 9 through which may be emitted fuel to be burned and whereby such fuel may be directed downwardly through the center of the cylindrical coil 7 to impinge on the top concave surface of the base 5. Within the base 5 of the burner, as shown in Fig. 2, is a chamber 10 into the bottom of which leads a fuel supply pipe 11 provided with a valve 12 as shown in Fig. 1, below which valve 12 the pipe 11 is shown as broken off, but such supply pipe 11 may be connected by any suitable means, not shown, with a source of fuel supply. A priming pan 13 is disposed beneath the base 5, such priming pan 13, being provided with an upwardly projecting hub 14 through which extends the pipe 11. The priming pan 13 is disposed to rest on a sheet 15 of asbestos or other non-combustible material which sheet 15 rests upon to cover and be supported by a grating 16 of the fire-box of an ordinary type of stove not shown, the sheet 15 thus disposed serves to prevent air from passing directly from the space beneath grate 16 into the fire-box space above the grate 16.

In a device of Fig. 1 I have provided an air-pipe 17 and an air-pipe 18 disposed on each of opposite sides of the burner with their axes inclined toward the vertical axis of the burner base 5 and supported by supporting plates 19 to extend through the sheet 15 from above the grate 16 into the space beneath said grate 16.

The air pipes 17 as shown in Fig. 1, extend upwardly inclining toward each other to terminate above and adjacent to opposite points on the upper edge of the cylindrical coil 7 while the pipes 18 likewise extend upwardly and toward each other to terminate near opposite points adjacent to the top edge of the base 5. Thus through the pipes 17 and 18 respectively air for combustion of fuel may be conducted from the space beneath the grate 16 upwardly to the top of the cylindrical coil 7 and to the top of the base 5. The lower ends of the pipe forming the coil 7, as shown in Fig. 2, are each provided with a screw-thread 20 which engage with a screw-thread within a bushing 21 which bushing 21 is screwed into holes provided in the top wall of base 5 where it is secured by a check-nut 22 thus to securely fasten in a vertical position the two end portions 6, 6

of the pipe. In the top of base 5, at opposite points on a line at a right angle to a line through the end portions 6, 6 are disposed two holes provided with a screw-thread which are plugged with screw-plugs 23, under some conditions of operation, but under other conditions one or both of such holes may be connected by pipes to a source of steam, compressed air or fluid fuel supply.

10 In the operation of a burner constructed as shown and described, the valve 12 is opened slightly to admit fluid fuel through the pipe 11 into the chamber 10 of the base 5 to fill it, thence to rise through each of the 15 end portions 6, 6 of the pipe and through the cylindrical coil 7 into the loop 8 to be emitted downwardly through the small hole 9 into and through the space within the coil 7 to drop onto the concave surface of the 20 top of base until such fluid fuel over flows to drizzle into the priming pan 13 until there be enough fluid fuel within said priming pan 13 for heating the coil 7 sufficiently to vaporize the fluid fuel whereupon the 25 valve 12 may be shut and the fluid fuel in the priming pan 13 ignited to burn till the coil 7 is heated to cause a vaporization of the fuel within said coil 7, the vapor from which will then flow downwardly through 30 the small hole 9 to burn within the coil 7 to cause the resultant flame to pass downwardly through the said coil 7 to be deflected outwardly by the concaved top of the base 5 and when the burner is sufficiently 35 heated the valve 12 may be opened again to a desired degree to regulate the flow of the fluid fuel at a rate for proper combustion, air for combustion being supplied through pipes 17 and 18 in an obvious manner.

40 In some instances, if desired, one or both of the plugs 23 may be removed and a pipe or pipes, not shown, may be connected to conduct steam or compressed air into the chamber 10 within the base 5 to mix with 45 the fuel therein more rapidly to volatilize or atomize the fuel before it is emitted from the small hole 9. The concave top of the base 5 by acting as a sort of auxiliary priming pan facilitates the heating of the 50 coil 7 which coil 7 by its tortuous course through a space of high temperature subjects the fuel within to such heat as will cause the fuel more readily to volatilize before reaching the point of combustion.

55 In Fig. 3 I have shown a plan view of the structure of Figs. 1 and 2.

In Fig. 4 I have illustrated a modified form of air pipes for conducting air to points of combustion wherein air pipes 24 are each supplied with a branch pipe 25 which branch pipe 25 terminates adjacent to the top edge of the base 5 while the main portion of each pipe 24 terminates above and adjacent to the top of the said coil 7 as

shown. Plates 26, 26 serve to support the 65 pipes 24 on the sheet 15 that rests upon a stove grate 16. Manifestly the structure of Fig. 4 is operative in the same manner as the structure of Figs. 1, 2, and 3.

Of course minor changes in the details of 70 construction of my invention may be made without departing from the spirit thereof.

What I claim is:

1. In a burner of the class described, the combination with a base portion which is 75 provided with a chamber adapted to receive fluid fuel, of conduit means for conducting fluid fuel into said chamber, a loop of pipe coiled and disposed to extend upwardly while its two ends are connected with the 80 top of said base portion to communicate with said chamber in said portion, the central portion of said loop of pipe being provided with a hole in its underside for the emission of fluid fuel, whereby fluid fuel 85 may flow from said chamber upwardly through both sides of said loop of pipe to and out of said hole thence downwardly therefrom into the space inclosed by said 90 loop of coiled pipe, and a priming-pan disposed beneath said base portion, suitably supported means for conducting air to points of combustion, and screw-plugged holes disposed in said base portion, said 95 holes being adapted to be unplugged and connected by conduit means with a source of supply of fluid under pressure.

2. In a burner of the class described, the combination with a base portion which is provided with a chamber adapted to receive 100 fluid fuel, of conduit means for conducting fluid fuel into said chamber, a loop of pipe coiled and disposed to extend upwardly while its two ends are connected with the 105 top of said base portion to communicate with said chamber in said portion, the central portion of said loop of pipe being provided with a hole in its underside for emission of fluid fuel, whereby fluid fuel may flow from said chamber upwardly through 110 both sides of said loop of pipe to and out of said hole thence downwardly therefrom into the space inclosed by said loop of coiled pipe, and a priming-pan disposed beneath 115 said base portion.

3. In a burner of the class described, the combination with a base portion which is provided with a chamber adapted to receive fluid fuel, of conduit means for conducting fluid fuel into said chamber, a loop of pipe 120 coiled and disposed to extend upwardly while its two ends are connected with the top of said base portion to communicate with said chamber in said portion, the central portion of said loop of pipe being provided with a hole in its underside for emission of fluid fuel, whereby fluid fuel may flow from said chamber upwardly through 125

both sides of said loop of pipe to and out of said hole thence downwardly therefrom into the space inclosed by said loop of coiled pipe, a priming-pan disposed beneath said base portion, and suitably supported means for conducting air to points of combustion.

5 In witness whereof, I hereunto subscribe

my name this twentieth day of January A. D., 1913.

JOHN J. MANN.
